CLAIM

The ornamental design for an automobile deodorizer, as shown and described.

DESCRIPTION

FIG. 1.1 is a bottom view illustration of an automobile deodorizer according to our new design.

FIG. 1.2 is a top view illustration thereof.

FIG. 1.3 is a front view illustration thereof.

FIG. 1.4 is a left side view illustration thereof.

FIG. 1.5 is a right side view illustration thereof.

FIG. 1.6 is a rear view illustration thereof.

FIG. 1.7 is a top, front, left side perspective view thereof. The broken lines shown in the drawings illustrate portions of the automobile deodorizer that form no part of the claimed design.
